UNITED STATES PATENT OFFICE.

DOMINIK BENKOVIC, OF MILWAUKEE, WISCONSIN.

CANDLE-HOLDER.

1,369,000.

Specification of Letters Patent. Patented Feb. 22, 1921.

Application filed March 22, 1920. Serial No. 367,681.

To all whom it may concern:

Be it known that I, DOMINIK BENKOVIC, a citizen of Czecho-Slovakia, and resident of Milwaukee, in the county of Milwaukee and 5 State of Wisconsin, have invented certain new and useful Improvements in Candle-Holders; and I do hereby declare that the following is a full, clear, and exact description thereof.

10 My invention relates to new and useful improvements in light supporting means, and pertains particularly to candle holders for use on Christmas trees and the like.

It is well known that at the present time 15 the candle holders which are used on Christmas trees are very inefficient, particularly in view of the fact that it is almost impossible to secure them to a tree in such a manner that the candles will remain upright. 20 Even those which, after considerable difficulty, are positioned to hold the candles upright, are thrown out of this position as soon as the branch of the tree begins to droop, consequently there is always danger 25 of fire when the candle holders of ordinary construction are used on a Christmas tree.

It is therefore the principal object of this 30 invention to provide a simply constructed candle holder which will automatically hold the candle carried thereby in upright position regardless of the position or inclination 35 of the supporting means such as a branch of a tree or the like. The obvious disadvantages which are incident to the use 40 of the ordinary Christmas tree candle holders is obviated by my invention.

A further object of the invention is to 45 provide a device of this character which can be manufactured quite inexpensively and consequently sold at a relatively slight cost.

Still another object of the invention is to 50 provide candle holders in which the candle carrying member is an extended portion of the main supporting element which engages the Christmas tree limb or the like.

With these general objects in view the invention consists in the novel features of construction, combination and arrangement of parts which will be hereinafter more particularly described and claimed.

In the accompanying drawing:

Figure 1 represents a substantially vertical sectional view of my improved candle holder, and

55 Fig. 2 is an elevational view of the holder

disposed in an upright position upon an inclined branch or the like.

Although the invention is designed primarily for use on Christmas trees, it is obvious that the principles thereof may be incorporated in candle or other like holders for use wherever it is necessary to retain such candle or the like in upright position. Therefore various changes may be made in the different parts of the illustrated embodiment of the invention without departing from the principles thereof or sacrificing any of the advantages.

Referring more particularly to the drawing, it will be seen that the invention consists essentially of a light carrying member 1, a light carrying member supporting means 2, and means 3 for automatically retaining the member 1 in upright or vertical position. The light carrying member 70 which receives a candle C consists of a coil of spring wire 4 having convolutions of a diameter substantially the same as that of the base of the candle C, and a cup or base plate 5 against which the bottom end of 80 the candle seats. The means 2 and 3 are formed from a pair of wires 6 and 7 which are twisted together at one end as at 8, while the other ends are spaced apart and each has a weighted ball or other shaped 85 member 9 secured thereto. Such an arrangement of the wires 6 and 7 provides a substantially inverted V-shaped member, the pendulum legs of which straddle a branch B or the like.

One of the wires forming said legs, for instance the wire 7, has its end portion adjacent the twist 8 soldered or otherwise secured as at 10 to the under side of the cup 5. The other wire 6 on the other hand, 95 although extended laterally in the same manner as the end portion 10, is disposed through a hole in the cup 5 and is connected to the lowermost convolution of the coil 4. This laterally extended part of the wire 6 100 is also soldered or similarly secured to the cup 5 to provide a rigid connection between the light carrying member supporting means and the light carrying member. In the preferred manner of constructing the 105 holder, the wire 6 which forms one of the pendulum legs is a continuation of the wire forming the coil 4 as shown in Fig. 1.

When in use the article is placed over the branch B or other support so that the legs 110

straddle the same whereupon the axis of the candle holder 4 is automatically moved to vertical position by the weights 9. Thus even though the branch or support B is continuously moving, the candle C will be retained in upright position. The disadvantages which have heretofore attended the use of lighted candles on Christmas trees are thus practically eliminated.

10 I claim:

A device of the class described comprising a base cup having a flat bottom with a hole therethrough at one side of the center thereof; a pair of leg wires twisted together and having their lower ends spaced apart, the upper end of one wire and the intermediate

portion of the other wire immediately above the twisted portions being extended laterally in opposite directions and secured to said base cup, the portion of said other wire 20 above said intermediate lateral portion being extended through said hole in the base cup and bent into a coil to receive a candle or the like, and weights on the free spaced lower ends of said leg wires whereby to 25 maintain the axis of said coil vertical.

In testimony that I claim the foregoing I have hereunto set my hand at Milwaukee, in the county of Milwaukee and State of Wisconsin.

DOMINIK BENKOVIC.
